UNITED STATES PATENT OFFICE.

WALTER A. CHANDLER, OF FALL RIVER, ASSIGNOR TO GEORGE DRAPER & SONS, OF HOPEDALE, MASSACHUSETTS.

SPINDLE-BEARING-ADJUSTING DEVICE.

SPECIFICATION forming part of Letters Patent No. 537,275, dated April 9, 1895.

Application filed January 3, 1895. Serial No. 533,704. (No model.)

To all whom it may concern:

Be it known that I, WALTER A. CHANDLER, of Fall River, county of Bristol, State of Massachusetts, have invented an Improvement in 5 Spindle-Bearing-Adjusting Devices, of which the following description, in connection with the accompanying drawings, is a specification, like letters and numerals on the drawings representing like parts.

10 In spinning and twisting machines having taper bladed spindles running in correspondingly tapered bearings, it is very important for the proper running of the spindle that its blade fits its bearing correctly, and to insure 15 and maintain a correct fit notwithstanding wear of the parts means must be provided whereby the bearing may be adjusted as necessary. I have devised simple and efficient means for this purpose, of such construction that the parts are simplified and so combined that the lateral bearing may be 20 adjusted vertically with relation to the spindle while the latter is running.

In accordance with my invention the lateral bearing is attached to a support mounted exteriorly on the supporting case, and shown as screwed upon the top of the case above the rail, rotation of the support upon the case raising or lowering the bearing and also preventing rotation of the latter. To prevent 30 accidental movement of the support I have provided a locking device to positively engage therewith under normal conditions.

Figure 1 in vertical section and partial elevation represents a spindle bearing embodying my invention. Fig. 2 is a transverse section thereof on the line $x-x$. Fig. 3 is a similar section on the line $x'x'$. Fig. 4 is an under side view of the support detached; and 40 Fig. 5 is a side elevation thereof.

Referring to the drawings, the spindle rail A and spindle B having a sleeve whirl B' are and may be of usual construction, the spindle being prevented from rising by means of a hook C, connected with the supporting case D containing the bolster bearing a and the step b. I have herein shown the spindle step b as a pin held in the bottom of the case D, and loosely entering the lower end of the 45 bolster bearing a, thereby serving to center its inner end. The upper end of the supporting

case is shown as provided with an annular recess or groove d, forming an oil reservoir, connected with the interior by suitable ducts d', the central hub or boss d² being externally 55 screw threaded to receive thereon the bolster bearing support, shown as a tube e, provided with an annular notched flange e' and internally threaded at its lower end at e², to engage the threaded boss d² on the supporting 60 case. The barrel of the support e is attached to the bolster bearing a in any suitable manner, shown as a pin 5 extended through the support into the bearing, which latter is internally tapered to receive therein the taper- 65 blade of the spindle B. By rotating the support in one or the other direction upon the supporting case D it will be, by means of the screw thread connection, raised or lowered, to effect thereby a relative vertical change of 70 position between the bolster bearing and the step b. The extended barrel of the tubular support e extends beyond the top of the lateral bearing a and practically forms a solid extension of the supporting case D, between 75 the bearing and the sleeve whirl B'. Oil holes a' are made in the wall of the lateral bearing a.

In order to absolutely prevent any accidental rotation of the support e and consequent change of adjustment of the lateral bearing a I have provided a positive locking device, herein shown as a spring finger a² held in the top of the case to normally enter one of the notches e² in the flange e' of the support. 80

When the bearing is to be adjusted the spring finger is withdrawn from the notch and the support e turned until the desired adjustment is effected, the finger springing 90 back into the adjacent notch.

It will be seen that the flange e' of the bearing support is at all times readily accessible, and that when it is desired to raise or lower the bolster bearing it is only necessary 95 to unlock and rotate the support, without at all interfering with the running of the machine at speed.

The bolster bearing may be readily removed with the support therefor by unscrewing the latter from the supporting case. 100

I claim—

1. The combination with a supporting case adapted to be fixed in a spindle rail, a spindle step therein, and an internally tapered bolster bearing, of a vertically adjustable support for the bolster bearing, mounted exteriorly on the case above the rail, to effect by its adjustment a relative vertical change of position between the bolster bearing and the step, substantially as described.
- 10 2. A supporting case adapted to be fixed in a spindle rail, a spindle step therein, and a tubular extension vertically adjustable on said case above the rail, combined with an internally tapered lateral bearing within the case and tubular extension, attached to and movable with said extension, movement of said extension varying the relative vertical position of the bearing and step, substantially as described.
- 15 3. A supporting case threaded at its upper end and adapted to be fixed in a spindle rail, a fixed spindle step, and a tubular extension adjustably mounted on the threaded end of the case, combined with an internally tapered hollow lateral bearing within the case and ex-

tension, attached to, and movable with said extension, and a tapered-bladed spindle in said bearing and resting on the step, rotation of the extension on the case effecting the vertical adjustment of the bearing relative to the spindle, substantially as described.

4. A supporting case containing a spindle step and adapted to be fixed in a spindle rail, a tubular support screwed upon the upper end of the casing, and an internally tapered bolster bearing within the case and support and movable with the latter, combined with a taper bladed spindle to enter the bearing and rest on the step, rotation of the support vertically adjusting the bearing, and a lock to engage and normally prevent rotation of said support, substantially as described.

In testimony whereof I have signed my name to this specification in the presence of two subscriving witnesses.

WALTER A. CHANDLER.
